UNITED STATES PATENT OFFICE.

JOSEPH B. FISCHER, OF CHICAGO, ILLINOIS, ASSIGNOR TO ERNEST A. TESCH,
OF CHICAGO, ILLINOIS.

FOUNTAIN MARKING-BRUSH

No. 846,558.

Specification of Letters Patent.

Patented March 12, 1907.

Application filed November 22, 1905. Serial No. 288,543.

To all whom it may concern:

Be it known that I, JOSEPH B. FISCHER, a citizen of the United States, residing at Chicago, in the county of Cook and State of Illinois, have invented certain new and useful Improvements in Fountain Marking-Brushes, of which the following is a specification.

This invention relates to improvements in brushes for use in marking or addressing boxes, packages, and devices.

My improved brush is constructed to hold a marking fluid which flows by gravity from a tubular handle through a nozzle or nipple upon a brush which extends from the nozzle and forms the fluid-applying element.

In the accompanying drawing, which forms a part of this application, Figure 1 shows in elevation my improved fountain marking-brush in condition for use. Fig. 2 is a longitudinal section through the device.

Referring to the details of the drawing, *a* represents a cylindrical tube the lower end of which is threaded internally and in the upper end is fixed an externally-threaded *25* plug *f*, which is adapted to be engaged by the tubular cap *a'* when the brush is in use.

b represents a nipple a portion of which is externally threaded to engage the lower end of the tube *a* and another portion of which is externally threaded, as at *b'*, to receive a tubular nozzle *c*. The nipple is centrally bored to provide a valve-chamber *b*³, having a seat which is adjacent to a passage *b*⁴. The nozzle *c* is formed with a chamber *c*², from which leads a passage-way *c'*, which extends through the tapering portion *c*³. The nozzle is also externally threaded to receive a tip *d*. The tip *d* is formed with a tapering bore somewhat larger in cross diameter than the *40* portion *c*³ of the nozzle, thus leaving an annular space between this portion of the nozzle and the inner walls of the tip. The tip is also externally threaded at one point to receive the cap *a'* when the brush is not in use.

Extending longitudinally of the tube is a valve-stem *e*, on the lower end of which is fixed a needle-valve *e'*, which controls the passage-way through the nipple *b*. The upper portion of the stem is enlarged and *50* threaded; as at *e*³, and such portion engages

the plug *f*. On the upper end of the stem a knob *e*² is secured to facilitate the operation of the valve.

g represents the bristles which form the brush proper, and these are arranged around the stem *c*³ of the nozzle and are clamped in place by screwing up the tip *d*.

Near the upper end of the tube a small hole is formed, which is controlled by a cover *a*², pivoted on the tube adjacent to the hole *a*³ and having a portion fitting the latter. When the device is in use, the cover is swung to one side, so as to uncover the hole and allow air to enter, so that the ink will flow freely to the brush.

The valve controls the quantity of fluid which will flow to the brush. The nipple, nozzle, and tip are all readily separable, so that they may be cleaned and new bristles inserted. By spreading the bristles around the tapering nozzle the marking fluid reaches the center of the brush and is thus distributed to the surface of the bristles, thereby making clean lines.

In filling the tube the nipple is unscrewed, *75* the cover closing the hole in the other end to prevent leakage at that point.

I claim—

In a marking device, a fluid-holding tube having an air-inlet opening in its upper end, *80* a closure for said opening, a nipple detachably secured to the lower end of said tube, said nipple having a valve-seat and a fluid-channel therein, a valve adjustably arranged in said tube and nipple, a tapering nozzle *85* detachably secured to said nipple, said nozzle having a chamber and a fluid-passage formed therein, a brush having portions of its bristles surrounding said nozzle, a sleeve adjustably mounted on said nozzle and adapted to *90* clamp the bristles around the nozzle, and a cap detachably secured to said sleeve and adapted to serve as a protector for said bristles.

In testimony whereof I affix my signature *95* in presence of two witnesses.

JOSEPH B. FISCHER.
